(57) **CLAIM**

The ornamental design for a container for intraocular lens, as shown and described.

DESCRIPTION

FIG. 1 is a front view of a container for intraocular lens showing our new design;
FIG. 2 is a rear view thereof;
FIG. 3 is a left side view thereof;
FIG. 4 is a top plan view thereof;
FIG. 5 is a bottom view thereof;
FIG. 6 is a perspective view thereof;
FIG. 7 is a sectional view thereof taken on line 7-7 of FIG. 1; and,
FIG. 8 is a sectional view thereof taken on line 8-8 of FIG. 3. A right side view is omitted because the right side view is symmetrical to the left side view.
